UNITED STATES PATENT OFFICE.

WILLIAM CHURCHILL, OF CORNING, NEW YORK.

DESIGN FOR A REFLECTOR FOR LAMPS.

No. 37,798.

Specification for Design.

Patented Jan. 30, 1906.

Application filed December 5, 1905. Serial No. 290,486. Term of patent 14 years.

To all whom it may concern:

Be it known that I, WILLIAM CHURCHILL, a citizen of the United States, residing at Corning, in the county of Steuben and State of New York, have invented a new, original, and ornamental Design for Reflectors for Lamps, of which the following is a specification, reference being had to the accompanying drawings, forming part thereof.

Figure 1 is a perspective view of one side of

a reflector, showing my new design. Fig. 2 is a perspective view showing the opposite side. Fig. 3 is an edge view.

I claim—

The ornamental design for a reflector for lamps, as shown.

WILLIAM CHURCHILL.
